(57) **CLAIM**

The ornamental design for a off-center opening for a teakettle, as shown and described.

DESCRIPTION

FIG. 1 is a side top perspective view of an off-center opening for a teakettle, showing our new design;

FIG. 2 is a top view thereof;

FIG. 3 is a front view thereof;

FIG. 4 is a side view thereof; and,

FIG. 5 is a rear view thereof.

The broken lines in the drawings are for illustrative purposes only and form no part of the claimed design.
